NONGLARE REFLECTOR

**William L. Bear, Dayton, and George R. Walker,
Oakwood, Ohio**

Application June 24, 1933, Serial No. 677,442

1 Claim. (Cl. 240—48.6)

This invention relates to new and useful improvements in non-glare reflectors.

It is one of the principal objects of our invention to provide a non-glare reflector for head-lights, searchlights and other illuminating devices.

Another object of our invention is to provide an auxiliary reflector for attachment to electric lamp bulb sockets in an easy and firm manner and having spaced concave reflecting and supporting shells integral at their peripheries.

It is another object of our invention to provide a non-glare reflector which is so constructed and arranged as to reclaim all waste rays for proper projection by the parabolic reflector behind it. No rays are wasted through ascension or descent.

It is another object of our invention to provide means for adjusting the position of the auxiliary reflector toward or away from the lamp bulb to protect its reflecting surface from the extremely high temperature of the lamp.

high temperature of the lamp.

Another object of our invention is to provide means for ventilating the space between the reflecting and supporting shells by forming in the latter a ventilating hole, behind the reflecting surface.

Other important and incidental objects will be brought out in the following specification and particularly set forth in the subjoined claim.

In the accompanying drawing illustrating our invention, Figure 1 is a sectional view taken through an adjustable headlight, showing our auxiliary reflector in its normal mounted position. Figure 2 is a plan view of the auxiliary reflector and its supporting frame. Figure 3 is a front end view of the auxiliary reflector and its support. Figure 4 is a rear end view of the auxiliary reflector support. Figure 5 is an inside view 35 of the urn-shaped auxiliary reflector shell. Figure 6 is a side view thereof. Figure 7 is a side view of a lamp bulb, the upper half of the end surface of which is silvered from the end of the filament to the outer extremity of the bulb. And 40 Figure 8 is a sectional view taken through the auxiliary reflector. And 45

In the accompanying drawings illustrating different forms of embodiment of our invention, the numeral 1 designates a conventional vehicle headlight provided with an outer casing 2, a parabolic reflector 3, a socket 4, lens 5 and a retainer ring 6.

Reflector 3, a socket 4, leads 5 and a retainer ring 6. Adapted to be inserted in the socket 4 is a dual filament bulb 7, although any other form of bulb may be employed if desired. Adapted to be applied to the lamp base 7a is the semi-circular

portion 8 of the inner end part of a U-shaped support 9 for an auxiliary reflector 10. The inner end part of the U-shaped support passes through one apertured end of a curved clamping band 11. The other apertured end of this band receives the threaded extension 12 of an eye piece 13 through which the inner end part of the U-shaped support also passes. Applied to the threaded extension 12 is a nut 14 which, when screwed inwardly, draws the clamping band 11 and the semi-circular portion of the U-shaped support tightly around the lamp base 7^a. (See Figures 1 and 4.)

The outer ends of the arms 14, 14 are threaded to receive inner nuts 15, 15 and outer shouldered nuts 16, 16. Between the shouldered ends of the nuts 16, and the nuts 15, the sleeve ends of a cross band 17 are fitted to the threaded outer ends of the arms 14. By means of the nuts 15 and 16 the cross band 17 may be held in an adjusted position on the U-shaped support 9. 20

At its middle portion the cross band 17 is formed with a loop 18 which is drawn tightly around a concave axial boss or projection 19 on an auxiliary reflector shell 10. The cross band is tightly held at the neck portion of the loop by a U clamp 20. 25

Directly opposite the clamp 20 the cross band is formed with a lip 21 that is bent through a recess 22 in the flange portion 23 of the reflector projection 19.

The U-member 9 and cross band 17 form a supporting frame for the auxiliary reflector 10, although any other suitable support may be provided if desired. This auxiliary reflector preferably comprises an inner glass semi-spherical member 10^a which is supported at its periphery within a substantially concentric outer supporting shell 10^b on which the projection 19 is formed and having therein a ventilating hole 24 that communicates with the space between the inner member 10^a and the outer shell 10^b as shown in Figure 8. The interior of the reflecting shell 10 is concaved as shown by the dotted lines in Figures 1, 2 and 6, so that it may be supported by the U frame in front of the bulb 7, with an air space of substantially uniform width between the outer surface of the bulb and the interior surface of the shell. In the position the auxiliary reflector occupies in Figure 1, the radius between the light source as a center and any point in inner surface 25 of the reflector, will be substantially the same, or that indicated by the arrow A in Figure 1. The heat insulation which the shell provides for the reflecting surface 25, permits a metallic silver coating to be applied, in this instance to the 55

upper half of that surface, without fear of its deterioration as a result of exposure to the intense heat of the lamp bulb.

The reflecting surface is further protected from the extremely high temperatures of the lamp bulb by the provision which we have made, through the nuts 15 and 16, for the adjustment of the auxiliary reflector shell. These nuts are adapted to hold the reflector in a desired position away from, or close to, the lamp bulb 7.

The glass reflector shell 10, with its rounded rim portion, is supported in such a manner that the center of curvature of its inner surface 25 is substantially the center of the source of light. The latter is the filament 26 of the lamp bulb 7, to which the inner end of the arrow A points in Figure 1. Being located a short distance from the periphery of the bulb, and having its upper half silvered as shown in Figure 5, the inner surface of the auxiliary reflector will reclaim the waste rays from the bulb and project them against the parabolic reflector 3, which in turn will direct them outwardly below the upper half of the auxiliary reflector to prevent glare.

There are other means for reclaiming, and di-

recting outwardly in a non-glare manner, the waste rays emitted by the lamp bulb. In Figure 7 we have also achieved this result by applying a silver coating 27 to a lamp bulb 28 adapted to be supported by the socket 4. This coating covers the upper half of the outer surface of the bulb, extending outwardly from the end of the double filament 29 to the extremity of the bulb.

Having described our invention, we claim:

The combination with a main reflector, a lamp socket and an electric lamp bulb in said socket in front of the main reflector, of a U-shaped member secured to the lamp base, the arms of said member projecting forwardly, one on each side of said lamp bulb, an auxiliary reflector comprising a semi-spherical shell having at its rear portion an axial boss containing a ventilating opening, a cross piece longitudinally adjustable along the outer ends of said arms, and a loop at the middle portion of said cross piece fitted to the axial boss on the auxiliary reflector to support the latter a desired distance in front of said bulb.

WILLIAM L. BEAR.

GEORGE R. WALKER.
